OF TEXAS.

STRAIGHT-LINE-LIFT PUMP JACK.

Application filed February 5, 1924. Serial No. 690,825.

To all whom it may concern:

Be it known that we, WILLIAM J. COLEGROVE and LEVI A. VANDERVOORT, citizens of the United States, residing at Ranger, in the county of Eastland and State of Texas, have invented certain new and useful Improvements in Straight-Line-Lift Pump Jacks, of which the following is a specification.

Our invention relates to pump jacks and more particularly to straight line lift pump jacks; and the object is to provide pump jacks composed of a combination of levers, links or fulcrum bars, and pins and fulcrums so arranged and assembled as to give a straight vertical lift on the pumping rods, the maximum and minimum lift being obtained through the proper ratio of levers, links and pins or fulcrums; to provide a pump jack in which the maximum length of stroke is regulated according to the size of the pump jack and the distance between fulcrum points and length of levers; to provide a pump jack in which there is a direct vertical lift so that by eliminating all side sways on the polish rods, friction on the stuffing box and polish rods will be reduced to a minimum, thereby eliminating waste through leakage around the polish rod and stuffing box which, in other structures, is the result of constant friction between polish rod and side of stuffing box; to provide a pump jack which is simple in construction and in operation and which can be operated with a relatively small amount of power and which is capable of operating at a higher degree of efficiency on account of there being no particular limit to the length of stroke which can be obtained; to provide a pump jack in which the amount of fluid raised will be increased over approved methods now in use on account of the long straight vertical line lift which can be obtained; and to provide a pump jack in which the minimum amount of strain, jerk or jar is produced on the pumping rods because of the slow motion with which the rods and column of fluid is started in motion, the speed being increased to a maximum near the center of the maximum stroke, slowing up again at the top of stroke, and giving the reverse motion on travel back to starting point.

Reference is had to the accompanying

drawings which form a part of this application.

Fig. 1 is a side elevation of a pump jack 55 constructed in accordance with our invention. Fig. 2 is a front elevation of the same.

Similar characters of reference are used to indicate the same parts throughout the several views.

The pump jack is provided with base frame members 1 and 2 and uprights 3 and 4 attached thereto and braced by web gusset plates 5 which are attached to uprights 3 and 4 and to the base frame members 1 and 2. An angular brace 6 is attached to upright 3 and to base frame member 1. A similar angular brace 7 is attached to upright 4 and to base frame member 2. The uprights 3 and 4 are braced by a cross-beam 8 at the lower or bottom ends and by a cross-beam 9 at their upper ends. The cross-beams 8 and 9 constitute spacing members.

The operating members include a pair of fulcrum bars 10 which are pivotally connected to the push bars 11 and to the pull bar 12. The bars 11 are pivotally connected to the cross-bar 9 which serves as a fulcrum for the push bars 11. The pull bars 12 are pivotally connected 75 to the cross-bar 8 which serves as a fulcrum for the bars 12 and the bars 12 are pivotally connected to the fulcrum bars 10. A pair of operating bars 14 are attached rigidly to the pull bars 12 by bolts 13. A pair of operating bars 14 are provided with a power transmitting bar 16 for operating the pump jack. The fulcrum bars 10 are connected by a lifting bar 17. The bars 12 and 14 are braced by bars 18 which are attached to the ends of the bars 12 and 14, forming triangles and providing relatively long leverage by which great power is obtained.

In operation, the bars 12 pull on the 95 upper ends of the fulcrum bars 10 and the bars 11 push on the lower ends of the bars 10. This compound application of the power causes the lifting bar 17 to move vertically upward on a power stroke, and when the power stroke is completed, the action of the bars 12 and 11 is reversed and the lift bar 17 moves vertically downward. It is apparent that power may be applied to the 100

bars 11, approximately at the points 19. It is apparent that the operating elements for causing a vertical movement of the lifting bar may be applied to both single and double acting pump jacks.

What we claim, is,—

1. A pump jack comprising a frame, fulcrum bars and a combined fulcrum and lift bar carried thereby, and means operatively connected to said fulcrum bars and frame for reversing said fulcrum bars and simultaneously elevating the same.

2. A pump jack comprising a frame of horizontal and upright members, reversible fulcrum bars and a combined fulcrum and lift bar carried thereby, operating levers fulcrumed on said frame members at their juncture and pivotally connected to said fulcrum bars at one end thereof and link bars pivotally connected to the upper end of said frame and pivotally connected to the other ends of said fulcrum bars and co-operating with said levers to lift said fulcrum bars and simultaneously to reverse the fulcrum bars as they are elevated for causing direct vertical movement of said lift bar.

3. A pump jack comprising a frame, levers fulcrumed on said frame, fulcrum bars pivotally connected at their ends to said levers, a fulcrum carried in the central portions of said fulcrum bars and serving as a lifting bar, means for actuating said levers, said levers co-ordinating with said fulcrum bars to produce on said lifting bar a slow movement produced by a relatively high ratio of said levers for giving a pow-

erful lift to said bar as compared to power applied at the beginning of movement.

4. A pump jack comprising a frame, fulcrum bars provided with a fulcrum serving as a lift bar carried thereby, means for suspending said fulcrum bars consisting of pulling levers connected to said frame and to said fulcrum bars at one end thereof, and pushing levers pivotally connected to said frame and to the other ends of said fulcrum bars, said pulling levers and pushing levers co-operating with each other to reverse said fulcrum bars and simultaneously elevate the same.

5. A pump jack comprising a frame, fulcrum bars provided with a fulcrum serving as a lift bar carried thereby, a pair of angular levers pivotally connected to the lower part of said frame and to said fulcrum bars at one end thereof, and a pair of pushing bars pivotally connected to the upper part of said frame and to the other end of said fulcrum bars, and an actuating bar for said angular levers.

6. A pump jack comprising a frame, fulcrum bars and a fulcrum therefor in the central portions of said bars serving as a lift bar, and levers pivotally connected to the ends of said fulcrum bars and to said frame for elevating said lift bar and simultaneously reversing said fulcrum bars.

In testimony whereof, we set our hands, this 18th day of January, 1924.

WILLIAM J. COLEGROVE.
LEVI A. VANDERVOORT.
